Patented June 4, 1974

231,754

CAMERA

Jerald Karel, 8847 N. Merrill Ave.,
Niles, Ill. 60648

Filed July 27, 1972, Ser. No. 275,709

Term of patent 14 years

Int. Cl. D16—01

U.S. Cl. D61—1 B

FIG. 1

FIG. 2

FIG. 3

FIG. 4

FIG. 5

FIG. 1 is a top plan view of a camera showing my new design;

FIG. 2 is a front elevational view thereof;

FIG. 3 is a rear elevational view thereof;

FIG. 4 is an end elevational view taken on lines 4—4 of FIG. 1, and

FIG. 5 is an end elevational view taken on lines 5—5 of FIG. 1.

The bottom is plain and unornamented.

I claim:

The ornamental design for a camera, as shown and described.
